UNITED STATES PATENT OFFICE.

JOHN FREDRICK SCHLAPPI, OF SIOUX CITY, IOWA.

FUEL ECONOMIZER.

Application filed November 23, 1925. Serial No. 71,013.

To all whom it may concern:

Be it known that I, JOHN FREDRICK SCHLAPPI, a citizen of the United States, and a resident of Sioux City, in the county 5 of Woodbury and State of Iowa, have invented certain new and useful Improvements in Fuel Economizers, of which the following is a specification.

This invention relates to furnaces and 10 more particularly to a preheating arrangement adapted to be employed in conjunction with certain elements of the preheater described and claimed in my Patent No. 1,489,853, dated April 8, 1924.

15 An object of the present invention is the provision of a device for heating air and for projecting the same over the bed of the fire so that the soot or other forms of unburned carbon which is carried off by the smoke and 20 gases will be consumed by the fresh supply of heated oxygen and thereby increase the efficiency of the furnace.

A further object of the invention is the 25 provision of a device for heating and distributing the heated air over the bed of a furnace and in which an enlarged chamber is provided for storing the air preliminarily to its heating which is in communication with a heating chamber having a plurality 30 of baffles which causes the air to take a tortuous path.

This invention will be best understood 35 from a consideration of the following detailed description, in view of the accompanying drawings forming a part of the specification; nevertheless it is to be understood that the invention is not confined to the disclosure being susceptible of such changes and modifications which shall define no material departure from the salient 40 features of the invention as expressed in the appended claims.

In the drawings:

Figure 1 is a view in perspective of my 45 preheater shown applied to a furnace door.

Figure 2 is a transverse vertical section of the heater.

Figure 3 is a vertical section of a modified form of the air heater.

50 Referring more particularly to the drawings, 10 designates a door which is hinged at 11 to the flanged opening 12 which forms an entrance for the insertion of fuel to the furnace 13.

55 The door is provided with a plurality of passages adapted to receive securing bolts

14 whereby the various sections of the pre-heater are bolted together and secured to the opposite faces of the door 10.

In Figure 2 a casing 15 is shown mounted 60 upon the front face of the door and is provided with a lower open end 16 forming an air inlet. In Figure 3 an inlet pipe 17 having a downturned portion open at its end and covered by a screen 18 is integrally 65 formed with the casing 15^a. The inner open edge as shown at 19 of the casing 15 in both forms is in engagement with the outer face of the door 10.

A second casing 20 has an open end in 70 contact with the inner face of the door 10 while the other end is provided with an annular flange 21 adapted to receive the inner end of a third casing 22. The casing 20 is adapted to normally project through 75 the opening 12 in the furnace when the door 10 is in closed position. The outer end of the casing 20 is provided with a closure 23 which is cut away as at 24 to provide an elongated air passage for connecting the 80 casing 22 with the casing 20 at their upper ends.

The casing 22 is closed at shown at 25 except for an elongated slot 26 at the lower end. A pair of baffles 27 and 28 project 85 inwardly from the inner face of the wall 25 and are not only integrally formed with said wall but also with the side walls 29 of said casing. The baffles 27 and 28 fall short of the width of the casing 22 so that spaces 90 30 and 31 are provided to provide air passages.

A third baffle 32 is formed integrally with the side wall 29 of the casing 22 and terminates short of the inner wall 25 in order to provide an air passage 33 between the free end of the baffle 32 and the wall 25. The inner end 34 of the baffle 32 is in contact with the outer face of the wall 23 of the casing 20.

100 The door 10 is provided with perforations through which the bolts 14 are inserted and the usual heads and nuts are employed for locking the sections 15, or 15^a, 20 and 22 in alined position and to the door so that the 105 casings are carried directly by the door. The door 10 is also provided with perforations 35 through which air from casing 15 may be admitted to casing 20.

The operation of my device is as follows: 110

Air passing through the tubular member 17 or through the port 16 enters casing 15 or

- 15^a and through passages 35 the air is admitted to casing 20 where it is initially heated. The heated air rises, passing over the top of wall 23 through the elongated slot 24 and into casing 22 where it is baffled by the member 28 and due to the suction in the furnace the heated air is then drawn through passages 30, 33 and 31 and then through the elongated slot 26 in the outer wall 25 of the 10 casing 22. The restricted and elongated slot 26 being located directly over the fire in the furnace supplies the flame with additional air which is heated so that particles of the smoke which are normally carried to the 15 chimney in an unburned condition is consumed due to its contact with the oxygen of the air so that the intensity of the flame is increased and the efficiency of the furnace is greatly improved.
- 20 This construction provides a chamber in the casing 15 or 15^a in which the air is preliminarily collected which passes to the initial heating chamber 20. This chamber being formed of metal is heated to a predetermined degree but not to the extent that the casing 22 is heated because of the fact that casing 22 is more directly located over the flame so that the air is heated progressively from casing 15 through casings 20 and 25 22 so that when it finally reaches the hot gases and smoke it will be in condition to cause greater combustion of the unconsumed particles of carbon which would otherwise be dissipated through the chimney.
- 30 The device shown in Figure 2 with the large port 16 is adapted for use in large furnaces, while the construction disclosed in Figure 3 is employed in the smaller furnaces used in houses.
- 35 What I claim is:
- 40 1. A fuel economizer for furnaces comprising a plurality of casings adapted to be secured together and supported by a furnace door, one of said casings having a closed end, the opposite end being in engagement with the furnace door, the closed end

being provided with an air inlet opening, the second casing having one end in engagement with the furnace door and alining with the first mentioned casing, the second casing 50 having the end open which engages the furnace door and the opposite end closed, a portion of the upper edge of the closed end of the second casing being provided with a slot, a third casing being alined with the second 55 casing and provided with a plurality of baffles extending horizontally and longitudinally of the casing for causing the air to assume a tortuous path through the third casing, the third mentioned casing having 60 its outer end closed with the closed end having a slot adjacent its lower end and below a baffle.

2. The combination with a furnace door and a fuel economizer, a plurality of casings 65 adapted to be secured together and supported by a furnace door, one of said casings having a closed end, the opposite end being in engagement with the furnace door, the closed end being provided with an opening, an air inlet conduit connected with the closed end and alining with the opening, the second casing having one end in engagement with the furnace door and alining with the first mentioned casing, the second casing 70 having the end open which engages the furnace door and the opposite end closed, a portion of the upper edge of the closed end of the second casing being provided with a slot, a third casing being alined with the 75 second casing and provided with a plurality of baffles extending horizontally and longitudinally of the casing for causing the air to assume a tortuous path through the third casing, the third mentioned casing having its 80 outer end closed with the closed end having a slot adjacent its lower end and below a baffle, the furnace door separating the first two casings from each other and being provided with openings for placing the chambers in communication with each other.

JOHN FREDRICK SCHLAPPI.
